DESIGN FOR A CONFECTIONERY PRODUCT

Norman M. Thomas, Pelham, N. Y., assignor to Joe Lowe Corporation, New York, N. Y., a corporation of Delaware

Application April 16, 1940, Serial No. 91,826

Term of patent 14 years

To all whom it may concern:

Be it known that I, Norman M. Thomas, a citizen of the United States and resident of Pelham, New York, have invented a certain new, original, and ornamental Design for a Confectionery Product, of which the following is a specification, reference being had to the accompanying drawing, forming part thereof.

Fig. 1 is a front elevational view;
Fig. 2 is a side elevational view; and
Fig. 3 is a top plan view of the confectionery product embodying my new design.

What I claim is:

The ornamental design for a confectionery product, substantially as shown.

NORMAN M. THOMAS.
